US00D631527S

(12) **United States Design Patent**
Swain et al.

(10) **Patent No.:** US D631,527 S
(45) **Date of Patent:** ** Jan. 25, 2011

(54) **KEY FOR A WATER FILTER ASSEMBLY**

(75) Inventors: **David Swain**, Palm Harbor, FL (US);
Edward C. Giordano, Fort Collins, CO (US)

(73) Assignee: **Paragon Water Systems, Inc.**, Clearwater, FL (US)

(**) Term: **14 Years**

(21) Appl. No.: **29/340,029**

(22) Filed: **Jul. 13, 2009**

(57) **CLAIM**

The ornamental design for a key for a water filter assembly, as shown and described.

DESCRIPTION

FIG. 1 is a top perspective view of a key for a water filter assembly;

FIG. 2 is a top plan view thereof;

FIG. 3 is a front elevation view thereof, the rear view being a mirror image of same;

FIG. 4 is a left side elevation view thereof; and,

FIG. 5 is a right side elevation view thereof.

The subject matter shown in broken lines is not considered part of the claimed design.
